MAGNIFIER

Stephen K. Bright, Perinton, N.Y., assignor to Bausch & Lomb Incorporated, Rochester, N.Y., a corporation of New York

Filed Dec. 7, 1967, Ser. No. 9,691

Term of patent 14 years

Int. Cl. D16—08

U.S. Cl. D57—1

Fig. 1

Fig. 2

FIG. 1 is a perspective view of a magnifier taken from a frontward elevated position showing my new design; and

FIG. 2 is a perspective view thereof taken from a rearward elevated position.

The underside, which is not shown in FIGS. 1 and 2, has essentially the same appearance as the top side shown in FIGS. 1 and 2.

I claim:

The ornamental design for a magnifier, substantially as shown and described.
